DESIGN FOR A LENS OR SIMILAR ARTICLE

George M. Cressaty, New York, N. Y.

Application May 9, 1945, Serial No. 119,467

Term of patent 14 years

(Cl. D48—1)

To all whom it may concern:

Be it known that I, George M. Cressaty, a citizen of France and a resident of New York, in the county and State of New York, have invented a new, original, and ornamental Design for a Lens or Similar Article, of which the following is a specification, reference being had to the accompanying drawing, forming a part thereof, wherein

Figure 1 is a plan view of a lens or similar article showing my new design,

Figure 2 is a sectional view thereof taken along line 2—2 of Fig. 1; and

Figure 3 is a bottom view.

The dominant features of my design reside in the portions shown in full lines.

I claim:

The ornamental design for a lens or similar article, substantially as shown and described.

GEORGE M. CRESSATY.
